(57) **CLAIM**

The ornamental design for a detail brush as shown and described.

DESCRIPTION

FIG. 1 is a front perspective view of a detail brush showing my new design;

FIG. 2 is a rear perspective view thereof;

FIG. 3 is a front elevational view thereof, the rear elevational view is identical;

FIG. 4 is a left side view thereof, the right side view is identical;

FIG. 5 is an enlarged top plan view thereof;

FIG. 6 is an enlarged bottom plan view thereof; and,

FIG. 7 is a partially enlarged view of area "7" shown in FIG. 1.

The dash-dash broken lines in the figures depict portions of the detail brush that form no part of the claimed design. The dot-dash-dot broken lines in the figures depict boundaries of the enlarged areas that form no part of the claimed design.
